D. J. STARR,
GARMENT STRETCHER,
APPLICATION FILED APR. 29, 1919.

1,330,356.

Patented Feb. 10, 1920.

UNITED STATES PATENT OFFICE.

DAVID JUDSON STARR, OF CINCINNATI, OHIO.

GARMENT-STRETCHER.

1,330,356.

Specification of Letters Patent. Patented Feb. 10, 1920.

Application filed April 29, 1919. Serial No. 293,465.

To all whom it may concern:

Be it known that I, DAVID JUDSON STARR, a citizen of the United States of America, residing at Cincinnati, in the county of 5 Hamilton and State of Ohio, have invented certain new and useful Improvements in Garment-Stretchers, of which the following is a specification.

The primary object of the invention is the 10 provision of a stretcher for garments especially designed for trousers whereby the same are held under tension in a pressed condition for any length of time desired until required for use.

15 A further object of the invention is to provide a trousers stretcher adapted for the ready reception of a garment, adjusting means being provided for accommodating the stretcher to garments of different length, 20 the invention being simple in construction, and easy and inexpensive to manufacture.

A still further object of the invention is to provide a garment stretcher adjustable in length having suspension means along the 25 axial line of the structure and with an adjustable resilient tension means guidingly mounted for preventing interference with the garment during the operation of the device.

30 With these general objects in view and others that will appear as the nature of the invention is better understood, the same consists of the novel combination and arrangement of parts hereinafter fully described in 35 connection with the accompanying drawing and in which like reference characters designate corresponding parts throughout the several views.

In the drawings,

40 Figure 1 is an elevational view of the invention ready for use,

Fig. 2 is an end elevation of the same partially broken away,

45 Fig. 3 is a transverse sectional view of the invention looking toward the opposite end thereof from that shown in Fig. 2,

Fig. 4 is an enlarged detail sectional view taken upon line IV-IV of Fig. 1,

Fig. 5 is an enlarged detail view taken 50 upon line V-V of Fig. 3,

Fig. 6 is an enlarged perspective view of an end portion of the longer head of the invention with a portion of the lining broken away, and

55 Fig. 7 is an inverted perspective view of

an end portion of the tensioning spring taken upon an enlarged scale.

My invention broadly comprises two clamping heads 10 and 11 adjustably connected together by a turn buckle member 12 60 while a resilient means 13 places the garment under tension during the holding operations.

The head 10 is shorter than the head 11 being adapted for receiving the lower end 65 of the transverse lugs, while the head 11 holds the body portion of the trousers.

The head 10 consists of a base plate 14 having one of the rod members 15 of the turn buckle means extending therethrough, 70 the plate 14 being adjustable upon the threaded end portion 16 of the rod 15 and held in its adjusted position by wing nuts 17 and 18 outwardly and inwardly of said plate respectively. A shiftable plate or jaw 75 19 is mounted upon the plate 14 by means of bolts 20 secured in the plate 14 and projecting through end slots 21 in the plate 19 while clamping nuts 22 upon the bolts 20 engage slotted bearing plates 23 adjacent 80 the slots 21.

The head 11 is similar in construction to the head 10 having its base plate 14' provided with the other or companion rod 15' of the turn buckle means extending therethrough while a shiftable or jaw plate 19' is mounted upon the plate 14' by means of bolts 20' projecting through slots 21' in the plate 19'. Clamping nuts 22' upon the bolts 20' engage bearing plates 23' adjacent the 85 slots 21'.

The inner threaded ends 24 of the rods 15 and 15' are provided with the usual form of connector 25 mounted thereon. A wing nut 26 upon the free end portion 27 of the rod 95 15' limits the outward movement of the head 11 away from the head 10. The resilient means 13 consists of a leaf spring adjustably secured upon the rod 15' by wing nuts 28 carried by the threaded portion 29 100 of the rod 15' for engaging opposite sides of the spring 13. Suitable guide means for the curved engaging ends 30 of the spring 13 are provided upon the adjacent edge of the base plate 14', this being herein illustrated in the form of angle plates 31, each having a lug 32 within a longitudinal groove 33 upon the lower side of the adjacent end 30. A suitable facing or lining 34 of felt or other material is provided upon the ad- 110

jacent inner faces of the plates 14' and 19' of the head 11 as well as the plates 14 and 19 of the head 10, the plates 31 being countersunk in the edge portions of the plate 14' with the lining 34 thereof positioned thereover as best illustrated in Figs. 4 and 6 of the drawing.

In operation, the heads 10 and 11 are drawn toward each other by means of the turn-buckle 25; the members 19 and 19' are then removed, which may be readily done by simply slackening wing nuts 22, 22', it being unnecessary to remove these wing nuts entirely to effect removal of members 19, 19'. The spring 13 at this time is in its relaxed position as shown by full lines in Fig. 1. The trousers 36 are then placed in position, the members 19, 19' replaced, and the trousers firmly clamped in the heads. The heads are then forced apart by means of the turn buckle which will compress the spring 13 to the proper degree, and any excess pressure exerted will force rod 15' through the member 19', thus allowing for any expansion or contraction of the fabric. The wing nut 26 is used merely to retain the parts together when not in use.

While the form of the invention herein shown and described is what is believed to be the preferable embodiment thereof, it is nevertheless to be understood that minor changes may be made in the form, combination, and arrangement of parts without departing from the spirit and scope of the invention as claimed.

What I claim as new is:—

1. In a garment stretcher, a pair of clamps, an adjusting rod connecting said clamps, one of said clamps including a base

plate slidably mounted upon one end of the rod, a leaf spring adjustably mounted upon said rod and having curved free ends slidably engaging the end portions of the inner edge of said base plate, and means adjustable upon the rod for limiting the outward movement of the base plate and for adjusting the base plate toward the other clamp while simultaneously compressing said spring.

2. In a garment stretcher, a pair of clamps, an adjusting rod connecting said clamps, one of said clamps including a base plate slidably mounted upon one end of the rod, angle members secured upon the ends of the inner edge of said base plate and having inwardly extending lugs, a leaf spring adjustably secured on said rod having curved free ends bearing upon said angle members and provided with longitudinal grooves slidably receiving said lugs, and means adjustable upon the rod for limiting the outward movement of the base plate.

3. In a garment stretcher, a pair of clamps, an adjusting rod connecting said clamps, one of said clamps including a base plate slidably mounted upon one end of the rod, a leaf spring having curved end portions and adjustably mounted on said rod, bearing plates upon the ends of the inner edge of said base plate and having inwardly extending lugs, the curved end portions of said leaf spring slidably engaging said bearing plates and provided with longitudinal grooves within which said lugs project, and means to limit the outward movement of said base plate.

In testimony whereof I affix my signature.

DAVID JUDSON STARR.
